TOBACCO HOGSHEAD

Kemper N. Moseley, 1014 Gloria Ave., Durham, N.C.

Filed Dec. 7, 1956, Ser. No. 627,040

1 Claim. (Cl. 217—44)

This invention relates to the handling and transportation of commodities such as tobacco, or other product of a leafy or generally similar character, and to a tobacco hogshead in which the tobacco is placed and which hogshead is adapted to be opened to permit the inspection and sampling of the tobacco contained within the same and subsequently replaced to recontain the tobacco.

The invention relates particularly to a tobacco hogshead in which the staves forming the wall portion between the two ends or heads is produced of two equal or generally similar parts or segments and such segments are fastened together to provide a complete side wall section of the hogshead.

Hogsheads used for containing tobacco have been made of staves produced from oak, pine or other lumber and have been fastened together by encircling hoops or bands of metal, which hoops or bands due to their length have been made of two parts, and the adjoining over-lapping portions of the hoops or bands have been connected by conventional fasteners such as split sleeve type fasteners. Staves previously used have been relatively thick and excessively heavy and easily broken because of knots and improper direction of the grain. Hogsheads produced of such staves have required excessive time in the opening of the hogshead to permit inspection and sampling and the closing of the hogshead after such sampling. Further the hoops or bands have been heavy and recoopering has been a complicated operation resulting in hogsheads of excessive costs.

It is an object of the invention to overcome the objectionable features in hogsheads previously produced and to provide a hogshead of simple and inexpensive construction, of lighter weight, of increased strength and in which cheaper lumber is used to provide a stronger and more durable structure.

Another object of the invention is to provide an improved hogshead of gum plywood of container grade in order to provide adequate strength of the stave and with heads of tongue and groove lumber or other material with battens by which the tongue and groove sections are fastened together, as well as a hogshead in which two-part bands are employed, which bands can be readily separated at one side of the hogsheads to afford opportunity for inspection, and sampling of the contents, but which bands can be readily and simply connected with a minimum of time and effort.

Other objects and advantages of the invention will be apparent from the following description taken in conjunction with the accompanying drawings wherein:

Fig. 1 is a perspective of a tobacco hogshead illustrating one application of the present invention;

Fig. 2, an exploded perspective of a tobacco hogshead opened for inspection of its contents;

Fig. 3, a perspective of one of the sections which is adapted to be connected to a similar section to form the side wall of the hogshead;

Fig. 4 is a plan view of the hogshead with the top and bottom removed;

Fig. 5, a perspective of one of the laminated staves with the liner or head retaining segment attached;

Fig. 6 a perspective of one of the two-part hoops or bands;

Fig. 7, a fragmentary perspective of a conventional

2

joint by which the ends of the two-part hoop or band are connected at one side of the hogshead;

Fig. 8, a perspective of the separable joint at the offset side of the hogshead from the connection of Fig. 7;

Fig. 9, a section on the line 9—9 of Fig. 8;

Fig. 10, an example of one of many types of force multiplication means susceptible of use in drawing the terminal loops of the hoop or band together; and

Fig. 11, a perspective of a bundle of half sections of Fig. 3, two of which can be put together to form the side wall of a hogshead.

Briefly stated, the present invention comprises a stave formed of three plies of equal thickness, such plies being composed of tough materials, such as gumwood, and the overall thickness of the three plies of equal thickness totaling approximately $\frac{1}{4}$ ". The plywood employed is of the container or better grade in preference to the cheaper or veneer grade and the three plies or laminae are bonded together with the usual adhesive material. The stave thus produced of plywood is relatively strong, although of less thickness and weight.

Each stave is provided on the same side adjacent each end with a liner which preferably is substantially square in cross-section to permit the head of the hogshead from popping out when subjected to stress or pressure, as well as to provide the necessary support for the end of the stave when the hogshead is stacked, turned on its end or side in such a manner that the end of the stave receives the weight of the filled hogshead or impact with another object or thing. The liners which are substantially square in cross-section have their ends tapered sufficiently so that when assembled with others of like character may intimately engage each other and form a circle. The contacting or abutting ends of the liners mutually support each other and consequently add strength to the hogshead.

In the production of the hogshead the side wall section formed by the staves and encircling hoops or bands is produced in two sections. In other words, before assembly the hogshead comprises a pair of ends and two sections of equal size which are combined to provide the finished hogshead. In view of the fact that the outside circumference of the hogshead formed by the staves and the slight space between them may be for example approximately 151", each half section will be approximately 75 $\frac{1}{2}$ ". Consequently, it is desirable, in order to reduce the length of the hoops or bands and the size of the package, to cut the bands in half and to make the side wall section in two parts which can be united to form the side wall of the hogshead.

With continued reference to the drawings, the hogshead of the present invention comprises a stave 10 of plywood composed of multiple plies, for example three, of equal thickness and the total thickness of the three being sufficient to provide the necessary strength in the stave. The plies or laminae of the stave may be any desired material having the necessary strength and toughness, for example, gum or other type of wood. However, the plywood is of the container or better grade and not of the veneer or cheaper grade and the plies or laminae are bonded together with the usual adhesive material. The plywood stave thus produced is of sufficient strength that it permits a thinner stave to be used, thereby effecting a saving in material, in weight and in transportation costs.

Each stave is provided adjacent opposite ends on the same side with a pair of liners 14, having beveled ends 15, such liners preferably being substantially square in cross-section to provide a relatively wide supporting area for the circular edge 16 of the head 17, composed of tongue and groove boards 18 and reinforcing battens 19, connected together by fasteners 20. Due to the breadth

and size of the relatively square liners, they provide the necessary support and reinforcement for the end of the stave when the weight of a hogshead rests on such end, as, for example, when the hogshead is up-ended or turned on its side, racked or stacked. The tapered or beveled ends 15 of the liners intimately engage each other when the hogshead is completely produced and form substantially a circle, the contacting ends of the liners abutting and mutually supporting each other and consequently adding strength to the hogshead.

For convenience in packing, shipping and handling, the heads of the hogsheads are made separately from the side wall units composed of staves with each unit being produced in two similar sections and including for example, thirteen staves slightly less than 6" wide and such staves held in edge to edge relation by means of half hoops or bands 21 and 22. The staves and half hoops or bands are fastened together by nails 23 or other fastening elements and the unit thus produced can be placed flat on a surface or with other units. For use, two of such units can be connected together to provide the circular wall of the hogshead. The hoops 21 are of a width to overlie the edges of the heads and are wider than the hoops 22.

The half hoops or bands are of a length so that they may be fastened together at one side of the barrel by a connector 24 in the form of a conventional fastener employed for connecting the ends of a strap ordinarily placed around a carton to hold the same closed. At the opposite end each of the half hoops or bands is bent reversely upon itself to provide a loop 25, the reversely bent portion of the band being fastened in place by a weld or other fastener 26.

The front of the loop also is provided with a cut 27 so that when two of such loops 25 are in position a U-shaped connector 28 can be inserted, and when struck with sufficient force by a hammer it will cause the cuts 27 in each of the loops to open and the central portion of the connector to substantially imbed itself between the sides of the cut. Thereafter the upper portion 29 of the loop beside the cut 27 can be struck with a hammer and bent over to retain the U-shaped connector in place.

In the production of the hogshead a pair of units composed of staves 10 and half hoops or bands 21 and 22 fastened together by nails 23, have their loopless ends fastened together by connectors 24 and their loop ends joined by U-shaped connectors 28. This side wall structure composed of the two units is placed upon the head 17 and the hogshead is then filled with tobacco which is compressed, and thereafter the remaining head is applied. If desired, in order to supply this second or upper head the connector 28 may be removed from the upper continuous loops so that the top of the hogshead can be spread slightly and the slats of the head can be worked into place by the use of a relatively flat lever, such as the conventional tire iron, not shown.

When it is desired to inspect and sample the tobacco within the hogshead, the connectors 28 may be readily knocked out or removed, similarly to the removal of bolts or pintles in the hinges of a door, the hogshead first having been stood on one end and the tobacco having formed an adhering mass or cake will be left resting upon the lower head, therefore affording access to the tobacco all the way from the bottom to the top of the cake. After the inspection and sampling the hogshead can be reassembled by placing the units composed of the two half hoops or bands with associated staves about the tobacco and the loops brought together in a manner to receive the connectors 28. Thereafter the upper head of the hogshead may be applied.

In order to make it possible for the workmen to apply sufficient pressure to the loops to bring them close together so that the connector 28 can be inserted, a pair of crossed levers 30 connected by a pivot 31 may be applied, the end of such levers being provided with par-

allel pins 32. By the use of the device the pins may be inserted in the loops 25 and the longer handles forced toward each other to bring together the opposite ends of the same to enable the connector to be inserted. In order to hold the parallel pins with the loops in contiguous relation, a ratchet type latch 33 may be attached to one of the levers and allowed to extend over and engage the arm 34 of the other.

A plurality of units may be placed in a stack as illustrated in Fig. 11 with the liners offset and such units, either packaged or not, may be shipped or handled with relative ease and whenever it is desired to construct a hogshead two of such units can be combined and their similar edges joined in the manner previously described.

From the foregoing it will be apparent that a hogshead is provided of lighter weight, of simplest and most inexpensive character, of stronger construction, the parts of which can be readily produced packaged and transported and from which the hogshead may quickly and easily be erected in a minimum of time with a minimum of effort and without the use of special tools or equipment or skilled labor, and can be opened for inspection and sampling and reclosed and resealed without damage to the contents, thereby simplifying the handling of tobacco, saving transportation costs, as well as permitting reuse of the hogshead.

It will be obvious to those skilled in the art that various changes may be made in the invention without departing from the spirit and scope thereof and therefore the invention is not limited by that which is illustrated in the drawings and described in the specification, but only as indicated in the accompanying claim.

What is claimed is:

A tobacco hogshead comprising duplicate units each including relatively thin laminated staves composed of inexpensive laminae and half hoops securing the staves of each group in edge-to-edge relation in a manner to permit the disposition of each unit in a single plane facilitating the stacking packaging and handling thereof, two of such units being adapted to have similar ends of the half hoops connected and with the separate connections at one side of the hogshead separable for inspection and sampling of the contents of the hogshead but capable of being readily reconnected by the application of force to the adjacent ends thereof to draw them near to each other to be held by a connector, the ends of said half hoops which provide the separable connection having loops, a removable U-shaped connector for securing said loops near each other so that when said connector is removed the connector ends of said half hoops will separate at one side of the hogshead when it is desired to permit inspection and after said inspection the hoops can be drawn together and said connector reapplied, each of said loops being split at one edge, so that leg portions of said U-shaped connector may be driven into said loops to spread the material of the loops at said splits, the material of said loops being deformable at said splits to grippingly retain the legs of said connector in place.
